UNITED STATES PATENT OFFICE.

TAYLOR FRED SUMMERS, OF TYLER, TEXAS.

LOADING DEVICE.

No. 926,619.

Specification of Letters Patent.

Patented June 29, 1909.

Application filed October 15, 1908. Serial No. 457,906.

To all whom it may concern:

Be it known that I, TAYLOR FRED SUMMERS, a citizen of the United States, residing at Tyler, in the county of Smith and State of Texas, have invented new and useful Improvements in Loading Devices, of which the following is a specification.

This invention relates to loading devices and more particularly to devices for loading the tenders of steam engines, and has for an object to provide means which may be constructed over a railroad track at certain intervals along the road and to construct the said device so that it may be automatically operated to load the tenders while trains are in motion.

A further object of this invention is to provide a device of this character with novel and effective means for preventing the discharge of coal into the tender should the engineer find the tender to be sufficiently full.

A further object of this invention is to provide a structure constructed over a railroad track and to provide a movable car or object which may be automatically set to deliver coal to cars moving in opposite directions.

Another object of the invention is to provide a novel form of conveyer for receiving coal from cars upon a side track and delivering the same at a point above the movable car or object wherein coal is to be deposited.

Other objects and advantages will be apparent as the nature of the invention is better set forth, and it will be understood that changes within the scope of the claims may be resorted to without departing from the spirit of the invention.

In the drawings, forming a portion of this specification and in which like characters of reference indicate similar parts in the several views:—Figure 1 is a side view of the loading device constructed over a railroad track, the device being in position to deliver coal to the tender of a moving train. Fig. 2 is a top plan view. Fig. 3 is an end view. Fig. 4 is a detail section taken on the line 4—4 of Fig. 2. Fig. 5 is a detail longitudinal section showing the manner of holding the car at one end of the device, the same being in a position to be released by a moving car. Fig. 6 is a detail side view of the lower portion of the coal car. Fig. 7 is a perspective view of the shaft and retainers for holding the gates of the coal car in closed position. Fig. 8 is a detail section through the locomotive cab showing the arrangement of trip levers.

Referring now more particularly to the drawings, there is shown a loading device 1 comprising vertically spaced uprights 2 and inner uprights 3, the latter being adapted to 60 straddle the main rails A of a track. The uprights 2 and 3 are connected to each other at their upper ends by longitudinally extending beams 4 and cross beams 5. The said uprights are suitably braced by means of 65 diagonally disposed bars 6, but it will of course be understood that the said uprights may be otherwise suitably braced to provide a rigid, strong and durable structure. The uprights 2 and 3 at the sides of the track A 70 are provided with members 7 disposed in parallel relation to each other and support transversely extending bars 8 which have portions extending inwardly of the uprights 3 and upon the said inwardly extending portions are mounted tracks 9. Bars 10 are located above the bars 8, are secured in a suitable manner to the uprights 2 and 3 and support tracks 11 disposed directly above the tracks 9. The members 7 are curved upwardly at their ends as indicated at 12, and the tracks 9 and 11 are curved upwardly in a like manner as shown at 13 for a purpose to be hereinafter more fully described.

A car or similar movable object is illustrated at 14 and is provided with an open top, as shown. The car 14 is divided by a partition 15 into compartments 16 and 17. The bottom of each compartment is closed by a gate 18 hinged as shown at 19 so that 85 the said doors may be swung outwardly. The car is provided with axles 20 and 21 which support at their ends wheels 22 to engage the tracks 9 and to move thereon longitudinally of the structure forming the device. 90 The cars are also provided with axles 23 and 24 disposed directly above the axles 20 and 21 and these axles are also provided at their ends with wheels 25 to engage the tracks 11. From this construction it will be seen that 100 the car may be moved in an effective manner and will resist considerable strain and will be held against displacement during its movement upon the tracks.

At one end, the frame is provided with a 105 horizontal axle 26 having a fixed pulley 27 at one of its ends. The axle 26 is provided midway between its end or at any other desired point with an indentation or recess 28 adapted to receive the hooked end 29 of an 110 arm 30 pivotally mounted upon the axle 20 of the car 14. The engagement of the hooked

end 29 of the lever 30 thus holds the car at one end of the frame 1. The pulley 27 has secured thereto one end of a cable or similar flexible element 31 which is guided over a pulley 32 at the lower end of one of the uprights 3 and has its terminal end secured to a lever 33 pivotally mounted as shown at 34 to the frame 1. The lever 33 preferably operates or in other words moves in a guide slot

10 35 formed in an arcuate member 36.

The construction just described sets forth elements of the device at one end of the frame 1. At the other end of the said frame a shaft 37 is provided which has fixed thereto 15 at one end or any other suitable point a pulley 38 to receive one end of a cable or the like 39, the other end of the said cable being secured to a lever 40 identical to the lever 33. The shaft 37 is identical with the shaft 26 and 20 is adapted to receive a lever 41 carried by the car 14 but which is disposed at the opposite end from that of the lever 30. It will be seen that the car 14 is thus adapted to be held at either end of the frame 1 for a purpose 25 to presently appear. It may be stated that the levers 33 and 40 are arranged at opposite sides of the track A to be operated by trains coming in opposite directions.

The bottoms of the compartments 16 and 30 17 are preferably inclined to permit ready discharge of coal. The gate 18 at the bottom of the compartment 6 is provided adjacent to its outer end with pins 42 one of which being adapted to receive a hook 43 at one end of a 35 shaft 44, and the other to receive a hook 45 at the other end of the said shaft 44. The hook 45 is provided with a depending lever or arm 46. As will be clearly seen in Fig. 6 of the drawings, the gate 18 of the compartment 16 is effectively held in a closed position. The gate 18 for the compartment 17 is identical to the just described gate and is held closed in identically the same manner, but it may be stated that the hook 47 is arranged 45 in line with the lever 46 of the hook 45 and the lever 48 is arranged in line with the hook 43.

A locomotive is shown at B and has attached thereto a tender C having at one side 50 a vertical arm 49 having an inwardly directed finger 50 at the upper end thereof. The locomotive B is provided with a lever 51 pivoted as shown at 52 to the interior of the said locomotive and the said lever has connected 55 thereto a suitable flexible element 53 passed through the locomotive and connected to a trip element 54'. From this construction it will be seen that when the lever 51 is moved into the dotted position shown in Fig. 8 the 60 trip element 54' will fall by gravity and assume a horizontal position, as shown in dotted lines in the said Fig. 8 so that it may operate one or the other of the levers 33 and 40 depending upon the movement of the locomotive.

Approximately at the center of the frame 1 and at the top thereof is shown a suitable enclosure 55 disposed directly above the track A and receives a downwardly inclined chute 56 of the desired construction. The lower 70 open end of the chute 56 is thus disposed between the uprights 3 as will be clearly seen upon reference to Figs. 3 and 4 of the drawings.

A longitudinally extending diagonally disposed conveyer frame is shown at 57 and the said frame, at the upper end is disposed directly above the chute 56. The frame 57 is provided at its lower end with a roller 58, and at the upper end the said frame is provided 80 with a roller 59. The just described rollers receive an endless conveyer 60 adapted to collect coal from a hopper 61 and convey the same upwardly to be discharged into the chute 56. The shaft for the roller 59 is provided with a pulley 62 adapted to receive a drive belt 63 from a motor 64 incidentally shown in the drawings and which is preferably located in the enclosure 55. To limit the downward swinging movement of the levers 30 and 41 I preferably provide the said levers with hooked inner ends 65 adapted for co-engagement with stop elements 66 upon the car 14.

In operation of the loading device as has hereinbefore been described the car 14 is moved beneath the chute 56 and coal is deposited into the hopper 61 to be collected by the endless conveyer 60 and carried upwardly to be discharged into the chute and 95 finally delivered to the compartments 16 and 17 of the car. If a sufficient quantity of coal has been delivered to the car 14 the said car is moved to the desired end of the frame 1. As shown in detail in Fig. 5, the car 14 is at 100 the left hand end of the said frame 1 and the lever 30 is engaged with the axle 26 to hold the car upon the upwardly curved portion 12. Assuming the locomotive B to be traveling in the direction of the arrow a in Fig. 1 110 of the drawings, it will be seen that the trip element 54' which has previously been set into an operative position will come in contact with the lever 33 moving the same in the direction of the arrow shown in Fig. 5 and 115 pulling against the cable 31 which operation will revolve the axle 26 to the extent that the hooked end 29 of the lever 30 becomes disengaged and by the provision of the curved portion 12 it is obvious that the car 14 is free 120 to travel by its own gravity to the position shown in Fig. 1 of the drawings. By reason of the fact that the locomotive is traveling at a faster rate than that of the car 14 it will be appreciated when the said locomotive is in 125 the position shown in Fig. 1, the car 14 is positioned directly above the tender C and by means of the finger 50 upon the arm 49 carried by the tender C it will be understood that the said finger will operate the lever 46 130

to the extent that the hooks 43 and 45 become disengaged from the beams carried by the gate 18 for the compartment 16 so that coal within the said compartment will fall by gravity into the tender. A single track is illustrated in the drawings and when the locomotive is traveling in an opposite direction to that just described the finger 50 engages the arm 48 to release the door of the compartment 17. Should it occur that the tender is sufficiently full of coal the engineer or fireman takes precaution and the trip 54 remains in an inoperative position so that it will not engage the levers 33 and 40, which consequently allows the car 14 to remain intact.

The frame 1 is provided at each end with a shaft 67 and each shaft is provided with a pulley 68. A cable 69 is passed over the pulleys and has its terminal ends secured to opposite ends of the car 14. The cable may extend directly through the inclosure 55 and may be operated or controlled by an operator therein. It will thus be seen that the car 14 may be conveniently moved from one end of the frame to the other depending upon the movement of the locomotive to receive coal.

While the device is particularly desirable for the described purpose of loading coal it will be understood that the device may be used for various loading purposes, and I do not desire to limit myself in this particular.

I claim:—

1. A loading device of the class specified comprising a car, a track for supporting said car adapted to permit the same to travel thereon by gravity, axles at the ends of said track, means upon the car for engaging said axles to hold the car against movement, and locomotive actuated levers connected with the axles so that they can be operated to disengage said means therefrom and permit the car to move by gravity into an operative position.

2. A loading device of the class specified

comprising a car, a track for supporting said car, locomotive actuated axles, means carried by the car for locking engagement with said axles to hold the car against movement, 50 said track having curved end portions adjacent to said axles so that when said means are disengaged from the axles the car will move by gravity into its operative position, and locomotive actuated means for releasing 55 the contents of said car when the latter is in its operative position.

3. A loading device of the class described comprising a track, a car mounted upon said track, said track having upwardly curved 60 end portions, revoluble axles at the ends of said track, means carried by the car for locking engagement with said axles, locomotive actuated levers connected with said axles and adapted to revolve the same to disengage 65 the said means therefrom and permit the car to move downwardly by gravity upon said curved portions, means for releasing the contents of the car when the latter is in its operative position, and means for moving said 70 car into its inoperative position after the discharge of its contents.

4. A loading device of the class specified comprising a track, a car movable upon the track, locomotive actuated axles, levers 75 upon the car having means for locking engagement with the axles to hold the car against movement normally, swinging gates at the bottom of the car, means for normally engaging the gates to hold them in their 80 closed positions, a chute disposed above the track, and a coal conveyer adapted to deliver coal to the chute and discharge the same into the car when the latter is in its discharge position.

In testimony whereof I affix my signature in presence of two witnesses.

TAYLOR FRED SUMMERS.
